DESIGN FOR A PHOTOGRAPH FOLDER

Ernest E. Koch, Forest Hills, N. Y.

Application January 25, 1944, Serial No. 112,320

Term of patent 3½ years

(Cl. D61—1)

To all whom it may concern:

Be it known that I, Ernest E. Koch, a citizen of no country and residing in Forest Hills, New York, have invented a new, original, and ornamental Design for a Photograph Folder, of which the following is a specification, reference being had to the accompanying drawing, forming part thereof.

graph folder in open position, showing my new design;

Figure 2 is a perspective view of the same in closed position.

I claim:

The ornamental design for a photograph folder, as shown.

ERNEST E. KOCH.
